UNITED STATES PATENT OFFICE

THOMAS HILL, OF DETROIT, MICHIGAN, ASSIGNOR TO DAN H. GILCHRIST, OF DETROIT, MICHIGAN

MOP

Application filed May 4, 1927. Serial No. 188,624.

My invention relates to mops.

An object is to provide a mop of simple, strong, sturdy construction wherein it is readily possible to quickly and easily wring the mop cloth without taking hold of it with the hands; wherein the mechanism is operable to stretch the cloth for drying; and wherein the several parts are so compactly and conveniently arranged and associated together 10 as to form a particularly efficient and useful structure.

My improved structure is of such a character that the mop head is adapted to be releasably locked within the line of the mop handle when the mop is adapted for use and is likewise adapted to be releasably locked within the line of the handle when the mop cloth is outstretched for drying; but the mop head is swung out of the line of the handle 15 when the mechanism is adapted for operation to accomplish the wringing of the cloth.

The several meritorious features, advantages, and superior characteristics of my improved structure will more fully appear from 20 the following specification, appended claims and accompanying drawing wherein one desirable illustrative embodiment of my invention is shown.

In the drawing:

30 Fig. 1 is a perspective of a mop embodying my invention wherein the cloth is stretched out for drying.

Fig. 2 is a perspective of the same mop structure wherein the cloth is disposed in 35 position for use.

Fig. 3 is an elevation partly broken away of my improved mop head.

Fig. 4 is a sectional view taken on line 4-4 of Fig. 1.

40 Fig. 5 is a sectional view taken on line 5-5 of Fig. 3, and

Fig. 6 is a perspective of a part of my mop structure.

In the embodiment of my invention shown 45 in the drawing, the mop handle 10 is provided at one end with a ferrule 12 having a pair of prongs 14 upon which is pivoted a mop head indicated in assembly as 16.

This mop head comprises a frame 18 piv- 50 oted at 20 upon the prongs 14. This frame

has at one end cooperating gripping members 22 between which the mop cloth 24 is held. One of these members is provided with a threaded sleeve extension 26 which projects through the other member and is 55 engaged by a nut 28 whereby the two members are drawn together.

The mop head is provided with a movable cloth engaging member 30 having a handle 32 extending slidably through the sleeve 26 of the member 22 whereby the cloth engaging member 30 may be moved toward or away from the gripping members 22. This handle 32 extends through the opposite end of the mop head frame 18 and up along the mop 60 handle 10 and is adapted to seat within a channel 34 formed within the handle 10.

The handle 32 is provided at its upper end with a hand grip portion 36 which is here shown as having a nut 38 that threads upon the handle 32 and a lock nut 40 is provided to hold it in place. This hand grip portion 36 and the nuts 38 and 40 are adapted to seat within a recess 42 formed in the handle 10 at the end of the channel 34 when the 65 parts are in the position shown in Fig. 2. In this position the mop is ready for use. The member 30 is provided with laterally projecting end portions 44 which serve to hold the cloth in place. This member 30 is 70 adapted when drawn back against the member 22 to seat between a pair of spaced apart ridges 46 formed on such member, with the end portions 44 abutting the ends of the ridges as shown in Fig. 2.

When it is desired to wring the mop cloth, the handle 32 is lifted out of the channel 34, the mop head pivoting upon its pivots 20 and the handle 32 is projected forwardly to stretch the cloth and then rotated which 75 serves to twist the mop cloth. The handle 32 is then projected forwardly to the extreme position and moved into engagement with the end of the ferrule 12, as shown in Figs. 1 and 4, at which position the cloth is held outstretched for drying. It will be seen that the handle 32 has two releasably locked positions, one as shown in Fig. 1 when the cloth is 80 stretched, and the other as shown in Fig. 2 when the handle 32 is seated in the channel 85 90 95 100

and the nuts 38 and 40 are seated within the recess 42.

What I claim is:

1. In a mop, a handle, a head pivotally supported upon one end of the handle, said head provided with a cloth gripping member, a cloth held by said member, a cloth engaging member on the head provided with a handle extending through said cloth gripping member and lengthwise the handle, said mop handle provided with a channel adapted to receive the handle of the cloth engaging member when the mop head is disposed within the line of the mop handle with the two cloth supporting members drawn together, said cloth engaging member handle adapted to be lifted out of said channel to swing the mop head out of the line of the mop handle.
2. In a mop, a handle, a head pivotally supported upon one end of the handle, said head provided with a cloth gripping member, a cloth held by said member, a cloth engaging member on the head provided with a handle extending through said cloth gripping member and lengthwise the handle, said mop handle provided with a channel adapted to receive the handle of the cloth engaging member when the mop head is disposed within the line of the mop handle with the two cloth supporting members drawn together, said cloth engaging member handle adapted to be lifted out of said channel to swing the mop head out of the line of the mop handle, and adapted to be moved lengthwise of the mop handle to project the cloth engaging member away from the cloth gripping member to stretch the cloth outwardly therefrom, means on the mop handle adapted to engage the handle of the cloth engaging member to hold the same in line with the mop handle and in the projected position.
3. A mop having a handle, a ferrule on one end of the handle provided with spaced prongs, a mop head pivoted upon said prongs to lie normally in line with the handle but adapted to be swung out of line therewith, means for locking the mop head within the line of the handle, said mop head provided with a pair of cloth supporting members, one of which members is stationary with the head and the other member is movable with respect to the first member to stretch the cloth outwardly therefrom, said movable member provided with a handle which extends lengthwise and is movable along the mop handle and is adapted to be releasably locked thereto at two different positions.
4. A mop having a handle and a head pivoted at one end of the handle to lie normally within the line thereof or to be swung out of line therewith, a cloth carried by said head, a part rotatably supported by the head adapted to be projected outwardly therefrom to stretch the cloth upon the head and to be rotated to twist the cloth, said part having

a portion extending along the handle of the mop and adapted to engage the handle at one position to lock the head in line therewith and to engage the handle at a second position to lock the head in line therewith with the cloth stretched upon the head, said handle so formed as to be engaged by said part at each of said two positions.

5. A mop having a handle, a head pivoted theron, said head provided with a cloth-gripping member and a cloth-engaging member, a cloth carried by said gripping member and engaged over said engaging member, said cloth-engaging member provided with a handle extending slidably through the cloth-gripping member and the cloth carried thereby and adapted to be projected slidably to stretch the cloth between said members and to be withdrawn to bring the cloth-engaging member against the cloth-gripping member, said cloth-engaging member handle extending rearwardly along the mop handle and adapted to be actuated to pivot the mop head upon the mop handle.

6. A mop having a handle, a mop head pivoted thereto to lie normally in a line therewith or to be swung out of line therewith, said head provided with a pair of cloth-engaging members, a cloth engaged over said members, one of said members provided with a handle extending slidably through the other member and having a bearing in a portion of the head above said member and slidably therethrough to stretch the cloth between said members and adapted to be locked to the mop handle to secure the head in line with the handle and to be lifted therefrom to pivot the head upon the mop handle, said mop handle provided with means adapted to engage the cloth-engaging member handle to lock the same in place thereon and said mop handle provided with a bearing for said cloth-engaging member handle.

7. A mop having in combination, a handle, a pair of clamping members pivotally supported upon one end of the handle, a cloth clamped between said members, a rod journaled through said members for rotation and axially slidably therethrough, said rod having a part at one end adapted to engage the end of the cloth remote from the handle and having a part at the other end adapted to be engaged to rotate the rod to wring the cloth.

8. A mop comprising, in combination, a handle provided at one end with a pair of arms, a cloth clamping device pivotally supported upon said arms to lie within the line of the handle or to be swung out of line therewith, a cloth carried by said clamping device, a rod extending through said clamping device and journaled therein for rotation and axially slidably therethrough, said rod having a part at its outer end adapted to engage the cloth at the end remote from the handle and having a part at its inner end adapted

to be engaged to rotate the rod to twist the cloth, said rod adapted to cooperate with the handle to lock the clamping device in the line of the handle.

5 9. A mop comprising, in combination, a handle having a head supporting fork at one end, a cloth clamping head pivotally mounted upon said fork to lie within the line of the handle or to be swung out of line therewith, 10 a cloth clamped by said head, a rod extending through said head and cloth and journaled therein for rotation and axially slidable therethrough, said rod having a transverse portion at its outer end engaging the cloth 15 and a transverse extension at its inner end whereby the rod may be rotated to wring the cloth.

10. In a mop, the combination with a handle, of a pair of arms carried thereby, a 20 cloth clamping member pivotally mounted on said arms, said member having a central aperture, another clamping member having an aperture adapted to register with that in the first mentioned clamping member, a bar 25 slidably mounted through said apertures, a cloth, means for holding the cloth clamped between said members, said bar having a laterally extending portion adjacent one end thereof, for engaging the cloth on that portion 30 thereof remote from the handle, and having the other end of the bar provided with means for enabling it to be rotated, and said bar functioning when so rotated to ring the cloth.

35 11. In a mop, the combination with a handle, a pair of clamping members carried thereby and pivotally mounted thereon, a cloth clamped between said members, and a rod slidably mounted through said members 40 and adapted to be rotated with reference thereto, said rod having one end thereof arranged to engage the end of the cloth remote from the handle, and having the other end terminating in a crank, whereby the rod may 45 be rotated to effect wringing of the cloth.

12. A mop having, in combination, a handle, a pair of clamping members pivotally supported upon one end of the handle, a cloth clamped between said members, one 50 of said members provided with an aperture, the other member provided with a tubular sleeve adapted to be received through said aperture and means engaging said sleeve to releasably clamp said members together and 55 a rod journaled within said sleeve and slidably axially therethrough having a part at one end adapted upon axial projection of the rod to engage the cloth at a point remote from the clamping members.

60 13. A mop comprising, in combination, a handle having a pair of spaced apart arms at one end, a pair of clamping members pivotally supported upon said arms, means adapted to releasably clamp said members 65 together, a cloth clamped between said members, a rod journaled through said members

for rotation and slidable axial movement having a part at one end adapted to engage a cloth and a part at the other end adapted to be engaged to rotate the rod, said rod extending normally lengthwise along the 70 handle and between said arms and adapted to be releasably secured to the handle to hold its cloth engaging part against said clamping members.

In testimony whereof, I, THOMAS HILL, 75 sign this specification.

THOMAS HILL.
